CLAIM

The ornamental design for a pair of buoyant shoes, as shown and described.

DESCRIPTION

FIG. 1 is a front elevational view of the pair of buoyant shoes of the present invention;

FIG. 2 is a rear elevational view of the pair of buoyant shoes of FIG. 1;

FIG. 3 is a left side elevational view of the pair of buoyant shoes of FIG. 1;

FIG. 4 is a right side elevational view of the pair of buoyant shoes of FIG. 1;

FIG. 5 is a top plan view of the pair of buoyant shoes of FIG. 1;

FIG. 6 is a bottom plan view of the pair of buoyant shoes of FIG. 1; and,

FIG. 7 is a top, front, right side perspective view of the pair of buoyant shoes of FIG. 1.

The broken away showing of the cord in the Figures indicate that it is of indeterminate length.
